UNITED STATES PATENT OFFICE.

WILLIAM C. HUNTOON, OF PROVIDENCE, RHODE ISLAND.

COLLAPSIBLE TUBE.

1,376,375.

Specification of Letters Patent. Patented Apr. 26, 1921.

Application filed July 24, 1919. Serial No. 313,025.

To all whom it may concern:

Be it known that I, WILLIAM C. HUNTOON, a citizen of the United States, residing at Providence, in the county of Providence and State of Rhode Island, have invented new and useful Improvements in Collapsible Tubes, of which the following is a specification.

This invention relates to certain new and useful improvements in collapsible tubes, and the primary object of the invention is to provide improved means for connecting the cap or closure to the neck of the tube so that the cap can be simply swung over the neck and then turned into threaded engagement therewith.

The invention in brief, proposes to form a ring or collar integral with the neck and at the base thereof, so as to form a circular groove receiving the cap fastener, while the upper face of the ring or collar provides a seat for the cap thereby to provide a tight sealed joint so as to exclude air from the tube contents.

25 In the drawings:

Figure 1, is a fragmentary side elevation of the invention;

Fig. 2, is a similar view parts being broken away and in section, the cap being shown in open position and

Fig. 3, is a section on line 3—3 of Fig. 1.

In proceeding in accordance with the present invention a tube 1, is provided having the usual frusto-conical end closing wall 2. The usual threaded neck 3 is formed with an integral collar or ring 4, which latter is spaced from the outer extremity of end wall 2, and is preferably grooved as indicated at 5. The usual cap 6, is formed with threads so as to have threaded engagements with the neck 3, and is provided with a groove 7, in which is received a wire bail 8, the latter being hinged or pivoted at 9, to a second bail 10, the bail 10, being received in the groove 5. It will be understood that each of the bails is freely

rotatable in the respective grooves 5 and 7. The ring 4, has its upper face formed to provide a seat for engagement with the base of the cap 6, so that the under face 50 of the latter positively and completely engages throughout its area with the upper face of ring 4. In this manner the bail 10 is held out of contact with the bottom of the cap 6, and the latter is thus provided 55 with a seat that is independent of the end wall 2, and acts to enable a perfect sealing relation to be obtained between the ring 4 and the cap.

These tubes are formed in a single operation, that is to say they are extruded by means of suitable dies so that all of the parts of the tubes, excepting of course the cap and its fastener, are formed out of a single piece of metal, so as to provide a single unitary structure. The ring or collar thus functions in a dual manner, namely affording a seat for the cap and an anchor for the cap supporting or hinging means.

Having thus described my invention, 70 what I claim as new and desire to secure by Letters Patent is:

In a collapsible tube having a threaded neck, a relatively thin metal ring integral with the neck and extending outwardly from 75 the threads and spaced above the upper end closing wall of the tube, and forming a groove with said end closing wall, a cap threaded over the neck, a bail encircling the cap, and a bail hingedly connected to the 80 first named bail and received in said groove, the upper face of the ring forming a seat for the rotatable cap so as to seal the tube neck against the ingress of air.

In testimony whereof I have signed my 85 name to this specification in the presence of two subscribing witnesses.

WILLIAM C. HUNTOON.
